UNITED STATES PATENT OFFICE.

KARL VÖLLER, OF DUSSELDORF, GERMANY, ASSIGNOR TO RHEINISCHE METALL-
WAAREN- UND MASCHINENFABRIK, OF DUSSELDORF-DERENDOE, GERMANY,
A CORPORATION OF GERMANY.

GUN-CARRIAGE.

1,119,629.

Specification of Letters Patent.

Patented Dec. 1, 1914.

Application filed February 20, 1914. Serial No. 220,003.

To all whom it may concern:

Be it known that I, KARL VÖLLER, engineer, a subject of the German Emperor, residing at 12 Scharnhorststrasse, Dusseldorf, Germany, have invented certain new and useful Improvements in Gun-Carriages; and I do hereby declare the following to be a full, clear, and exact description of the invention, such as will enable others skilled in the art to which it appertains to make and use the same.

The present invention relates to gun carriages intended for guns which have a large angle of traverse and its object is to increase the stability of such gun carriages when firing in extreme positions of traverse. For this purpose, on the transom connecting the two cheeks of the gun carriage, which are spread apart rearwardly, trails are attached in such a manner that they can be transferred from the center of the transom to the ends thereof when the gun is fired in a position of extreme traverse.

The invention is illustrated in the accompanying drawings, Figure 1 being a side elevation of a gun carriage constructed according to the present invention and Fig. 2 a plan view of the same. Figs. 3 and 4 show, on an enlarged scale, a section and a plan view of the means for fastening the trail to the ends of the transom.

The gun carriage cheeks *a* are arranged divergently and connected at their rear ends by a transom *b*. To this transom *b* two trails *e* are connected, close to the middle of the transom. Each trail *e* is provided at its free end with a plate *c* and spade *d* and when in this central position they can be held together by means of the limber hook *f* and two eyes *g* which overlap.

If the gun is to be fired with an extended angle of traverse, the trails *e* are removed from their central position by withdrawing the bolts *g* and are then secured to the ends of the transom *b* as shown in Fig. 2 in dot-

ted lines. As shown in Figs. 3 and 4 at each end of transom *b* there is journaled a worm *h* which engages, when the trails are attached to each end of the transom, with a worm segment *i* fixed to each trail. By means of these worm gearings the trails can be adjusted vertically to allow for unevenness in the level of the ground.

I claim as my invention:

1. A gun carriage having divergently-arranged cheeks, a transom connecting the outer ends of said cheeks, trails extending rearwardly from the transom, and means for connecting the trails to the transom at a plurality of points. 55

2. A gun carriage having divergently-arranged cheeks, a transom connecting the outer ends of said cheeks, trails extending rearwardly from the transom, and means for connecting the trails to the transom at 65 or near the center thereof and also at its ends.

3. A gun carriage having divergently-arranged cheeks, a transom connecting the outer ends of said cheeks, trails extending 70 rearwardly from the transom, means connecting the trails to the transom at a plurality of points and means for vertically adjusting the trails.

4. A gun carriage having divergently-arranged cheeks, a transom connecting the outer ends of said cheeks, trails extending rearwardly from the transom, means connecting the trails to the transom at a plurality of points and means for vertically adjusting the trails while secured to the transom. 75

In testimony whereof, I have signed this specification in the presence of two subscribing witnesses.

KARL VÖLLER.
